CLAIM

The ornamental design for a lock for pickup truck rear window, as shown and described.

DESCRIPTION

FIG. 1 is a top, front and end perspective view of the lock for pickup truck rear window embodying the design of the present invention;

FIG. 2 is a front elevational view thereof, the rear being a mirror image of the front shown in FIG. 2;

FIG. 3 is an end elevational view thereof, the end opposite being a mirror image of the end shown in FIG. 3;

FIG. 4 is a top plan view thereof; and,

FIG. 5 is a bottom view thereof.

FIG. 1

FIG. 2

FIG. 3

FIG. 4

FIG. 5
